COMBINED SEESAW AND SWING

Jesse James Carter, Bowling Green, Ky.

Application June 3, 1939, Serial No. 277,287

7 Claims. (Cl. 272—54)

My invention relates to a combined seesaw and swing especially adapted for installation and use in playgrounds, such as school yards, the invention contemplating an arrangement in which the swing portion thereof may be operated in conjunction with or separate from the seesaw portion thereof, and an important object of my invention is to provide a simple and efficient arrangement of this character which can be cheaply and strongly constructed of readily available material, such as pipe, pipe joints, and pipe couplings.

Other important objects and advantages of my invention will be apparent from a reading of the following description in connection with the drawings wherein for purposes of illustration I have shown a preferred embodiment of my invention.

In the drawings:

Figure 1 is a general side elevational view of 20 the embodiment.

Figure 2 is a top plan view thereof.

Figure 3 is an enlarged transverse vertical sectional view taken through Figure 1 approximately on the line 3—3 and looking toward the right in the direction of the arrows.

Figure 4 is a transverse vertical sectional view taken approximately centrally through Figure 1 at one side of the middle member of the device.

Figure 5 is a fragmentary perspective view of 30 one of the swing supports.

Figure 6 is a fragmentary perspective view of the middle portion of the seesaw board.

Referring in detail to the drawings, the numeral 5 generally designates a suitable base, which in the case of a permanent installation, may be a concrete or other suitable material platform, the base having rising from the opposite end portions thereof the transversely spaced pipe sockets 6, 6, and 6', 6', respectively, which are secured in a suitable manner to the base 5. Having their lower ends seated in these sockets are the respective standards 7, 7 and 8, 8 which have respectively T-couplings 9, 9 and 10, 10 threaded on the upper ends thereof. Into the upper end of the standard portion of the couplings mentioned are threaded the vertical arms 11 of the laterally projecting pairs of arms 12, 12 and 13, 13 which are upturned at their laterally outward ends as shown. Extending from the horizontal arms of the T-couplings are guy rods or pipes 14, 15 which are parallel and extend longitudinally and have the middle portion thereof passed through respective tubular fittings 16, 17 which are elevated above the fittings 9, 55

9 and 10, 10 and have depending flanges 18 through which are journaled the horizontal transverse laterally extending arms 19, 20 of the central member which is generally designated 21 and which has the depending U-shaped portion 22 at its center, the arms of which are seated in notches 23, 24 cut in the opposite sides of the middle of the seesaw board 25, as indicated in Figures 2, 4 and 6. The laterally outward terminals of the arms 19 and 20 of the central member 21 are threaded in elbow couplings 26, 27 from which depend the central member arms 28, 29 which terminate at their lower ends in laterally outwardly projecting pintles 30, 31 (see Figure 4), the outer ends of these pintles being threaded and provided with respective nuts 32 and 33 to retain on the pintles the eyes 34, 35 on the longitudinally inward ends of the pairs of connecting rods 36, 37 and 38, 39 at the opposite sides of the swing. The longitudinally outward ends of the various connecting rods have eyes 40 which are engaged through eyes 41 depending from the bottom of the various swing seats at the laterally inward side thereof, the eyes 41 being formed on the lower ends of the longitudinally inward legs 42 of the laterally inward support 43 of each swing, each swing being composed of an inverted hairpin-shaped support or suspension arrangement comprising the laterally inward member 43 and the laterally outward similar member 44. The swing consists of a seat 45 in the form of a plate or board, an inclined back 46 rising from the rear end of a plate 45, sides 47 and 48 located inwardly of the lateral edges 49 of the plate 45 with the suspension members 43 and 44 located laterally outwardly of the said sides 47 and 48, with armrests 49 on the upper ends of the said sides through which lower portions of the suspension members 43 and 44 pass as well as through the lateral edge portions of the plate 45, under which plate the various legs have nuts 50 threaded thereon against the bottom of the said plate. The bight portion 51 of the suspension members bear swingably on the lateral arms 13 of the swing supports 8. Footrests 45' are secured to depend from the forepart of the seat plates 45.

Extending horizontally between the respective pairs of swing supports are the upper and lower cross members 52 and 53 which have T-fittings 54 at their laterally outward end with the tubular cross head thereof slidably receiving the swing support standards 7, 7 or 8, 8, set screws 55 being provided in the said fittings for locking the cross members in place.

The seesaw board 25 consists of a suitable length of plank or the equivalent which when tiltably mounted as already indicated on the middle member 21 extends its opposite ends beyond the pairs of swings as clearly shown in Figures 1 and 2, and longitudinally outwardly located with respect to the pairs of swings are the seesaw seats 56, 57 which are of a suitable bucket type firmly secured on the top of the seesaw board, with foot rests 58 and 59 located longitudinally inwardly of the seesaw seats and attached like brackets to the lateral edges of the seesaw board as indicated by the respective numerals 60 and 61. Longitudinally inwardly of one of the seesaw seats there is pivoted to the lateral edge of the seesaw board as indicated by the numeral 62, a lever 63 which has pivoted to its lower end as indicated by the numeral 64 one end of a connecting rod 65 which is pivoted at its other end as indicated by the numeral 66 to a collar 67 which is suitably secured in place on the upper part of the depending members 29 of the middle member 21, this lever being so arranged that the occupant of the seesaw seat 57 may by rocking the lever 63 cause operation of the swings in conjunction with and in synchronism with the seesaw board 25, or at his option position the said lever so that the seesaw board may be operated independent of the swings.

Rope handles 68 depending from the seesaw board near the swing seats enable the occupants thereof to start the swing going.

Although I have shown and described herein a preferred embodiment of my invention, it is to be definitely understood that I do not desire to limit the application of my invention thereto, and any change or changes may be made in the structure and arrangement of the parts, and in the materials employed, within the spirit of the invention and the scope of the subjoined claims.

Having described the invention, what is claimed as new is:

1. A device of the character described comprising a base, pairs of swing supports rising from opposite end portions of said base, laterally outwardly projecting swing arms on the upper part of said swing supports, individual swings suspended from said swing arms, a middle member located between said pairs of swing supports, means supportably and swingably engaging the upper part of said middle member and extending between the upper ends of the respective swing supports and said middle member, and pairs of connecting rods pivotally connected at their longitudinally inward ends to the lower part of said middle member and at their longitudinally outward ends to the respective individual swings, whereby said individual swings and said middle member operate in unison.

2. A device of the character described comprising a base, pairs of swing supports rising from opposite end portions of said base, laterally outwardly projecting swing arms on the upper part of said swing supports, individual swings suspended from said swing arms, a middle member located between said pairs of swing supports, means supportably and swingably engaging the upper part of said middle member and extending between the upper ends of the respective swing supports and said middle member, and pairs of connecting rods pivotally connected at their longitudinally inward ends to the lower part of said middle member and at their longitudinally outward ends to the respective individual swings, whereby said individual swings

and said middle member operate in unison, said upper part of the middle member comprising a cross bar, a seesaw board having its center resting on said cross bar, means holding the seesaw board in place on said cross bar.

3. A device of the character described comprising a base, pairs of swing supports rising from opposite end portions of said base, laterally outwardly projecting swing arms on the upper part of said swing supports, individual swings suspended from said swing arms, a middle member located between said pairs of swing supports, means supportably and swingably engaging the upper part of said middle member and extending between the upper ends of the respective swing supports and said middle member, and pairs of connecting rods pivotally connected at their longitudinally inward ends to the lower part of said middle member and at their longitudinally outward ends to the respective individual swings, whereby said individual swings and said middle member operate in unison, said upper part of the middle member comprising a cross bar, seesaw board having its center resting on said cross bar, means holding the seesaw board in place on said cross bar, seats on the opposite ends of said seesaw board positioned longitudinally outwardly from the adjacent pairs of individual swings.

4. A device of the character described comprising a base, pairs of swing supports rising from opposite end portions of said base, laterally outwardly projecting swing arms on the upper part of said swing supports, individual swings suspended from said swing arms, a middle member located between said pairs of swing supports, means supportably and swingably engaging the upper part of said middle member and extending between the upper ends of the respective swing supports and said middle member, and pairs of connecting rods pivotally connected at their longitudinally inward ends to the lower part of said middle member and at their longitudinally outward ends to the respective individual swings, whereby said individual swings and said middle member operate in unison, a seesaw board rockably mounted on said middle member, a lever pivoted between its ends adjacent one end of said seesaw board, a connecting rod pivotally connected to one end of said lever and to a portion of said middle member below said seesaw board, said lever being arranged to be positioned and held by an occupant of the corresponding end of said seesaw board to produce operation in unison of said swings and said seesaw board.

5. A device of the character described, said device comprising a pair of spaced standards, a pair of laterally spaced longitudinal support members extending between and connected rigidly to the upper part of said standards, bracket means mounted at the approximate longitudinal middle of said longitudinal support members, an inverted U-shaped vertically disposed middle member comprising a horizontal cross bar turning in said bracket means and legs depending from spaced points along said cross bar, laterally outwardly extending swing supporting arms on the opposite sides of the upper part of said standards, a swing depending swingably from each of said arms, a connecting rod for each swing, said connecting rod being pivoted at its longitudinally outward end to the swing and at its longitudinally inward end to the lower end of the adjacent one of said legs of said middle member, whereby the swings operate in unison.

6. A device in accordance with claim 5 com-

prising a seesaw board swingably resting on the said cross bar of said middle member and extending longitudinally beyond said standards, means located at the middle of said seesaw board for preventing longitudinal and lateral shifting of said seesaw board relative to said cross bar.

7. A device in accordance with claim 5 comprising a seesaw board swingably resting on the said cross bar of said middle member and extending longitudinally beyond said standards, means located at the middle of said seesaw board for preventing longitudinal and lateral shifting

of said seesaw board relative to said cross bar, a start and stop lever pivoted to said seesaw board adjacent one end thereof, and a rigid rod pivotally connected to a free end of said lever and to a leg of said middle member enabling the occupant of the said end of the seesaw board to cause the seesaw board to be operated in unison with and by operation of the swings or to permit the seesaw board to be operated or rendered inoperative independently of the swings.

JESSE JAMES CARTER.
